Patented July 29, 1919.

FIG. 2.

Inventor
J. A. Butcher.

John A. Butcher

Attorney

UNITED STATES PATENT OFFICE.

JOSEPH A. BUTCHER, OF SULPHUR, LOUISIANA.

OIL-TANK.

1,311,753.

Specification of Letters Patent. Patented July 29, 1919.

Application filed July 27, 1915. Serial No. 42,220.

To all whom it may concern:

Be it known that I, JOSEPH A. BUTCHER, a citizen of the United States, residing at Sulphur, in the parish of Calcasieu and 5 State of Louisiana, have invented certain new and useful Improvements in Oil-Tanks, of which the following is a specification.

This invention relates to improvements in oil tanks generally, more especially for 10 guarding the same against explosions from lightning.

The invention has for its object to carry out the aforesaid end in a simple, inexpensive and effective manner.

15 The invention consists therefore of certain instrumentalities and features of construction substantially as hereinafter fully disclosed and defined by the appended claims.

20 In the accompanying drawings is illustrated the preferred embodiment of my invention wherein it will be understood that various changes and modifications may be made as to the detailed construction and arrangement of parts without departing from 25 the scope of the claims, and in which drawings—

Figure 1 is a sectional elevation thereof, the roof or closure being in place.

30 Fig. 2 is a horizontal section, taken just above the outlet or delivery pipe connection.

In carrying out my invention, I provide the tank or holder 1 with a shallow water-holding receptacle 2, suitably secured by 35 bolts or otherwise within the upper end, of the tank; a frame or additional support 3 therefor being also secured thereunder and to said tank, said frame being constituted preferably of centrally crossing bars.

40 Upon the tank or holder 1 is suitably superposed a conical roof or protector 4, with its rafters 5 secured to horizontal beams 6 suitably secured upon the top-edge of the tank or holder, said roof or protector having 45 its sheathing of asbestos or other non-inflammable material 7 and, yet in event of any portions of the roof becoming mutilated or otherwise rendered non-protective from fire or lightning the falling, or fragmental,

50 portions thereof would be received within the water-receptacle 2 and thus be prevented from contact with the oil in the tank, accordingly guarding against firing the oil.

A suitable inlet-pipe or intake 8 connects 55 with the tank or holder 1, about centrally of

its bottom, for supplying the oil to the tank the oil being delivered or taken therefrom by means of an outlet-pipe or outtake 9. The pipe or outtake 9 communicates with the tank, just below the water-receptacle 2 and 60 is adapted at that point to receive and carry off accumulating gas upon the oil-surface, as well as to perform its primary function of delivering the oil from the tank. The pipe 9 is carried downwardly under or below the 65 surface of the ground about two feet and has a horizontal extension or portion 10 and this latter has an upward extension 11, with a suitable T-terminal 13 for the suitable attachment thereto of branch-pipe (not 70 shown) as may be called for in distributing the oil for use. The pipe-extensions 10, 11 are suitably incased or protected in tiling (not shown), as well understood. The pipe-extension 10 is equipped with a suitable 75 plug-valve 12 for cutting off the ignited or burning oil in event of the same taking fire, from the source as above indicated, at the discharge end as at 13 of the delivery pipe, the same being the more exposed, above 80 ground, and, of course, likely to receive a lightning stroke. At the opposite side of the oil tank or holder 1 is a screw-plug 14 adapted to be removed in event of the appearance of flame at that side of the tank, or 85 for the venting of the tank for the escape of gas-accumulations, in the event of an emergency as just described owing to the valve or plug 12 being then closed, as above indicated.

90 What I claim as new is:

1. In a roofed oil tank having vent means and an outlet opening arranged in the upper portion thereof, crossed supports arranged in the upper portion of the tank and having their respective ends secured to the 95 walls of the tank, a water receptacle of a contour similar to the contour of the tank having its walls snugly engaged with the inner surface of the walls of the tank and its bottom resting on the supports so that the upper edges of the walls of the receptacle lie flush with the upper edges of the walls of the tank, and means for securing the walls of the receptacle and tank together.

2. The combination with an oil tank having an open top and vent means and an outlet opening arranged in the upper portion thereof, and a superimposed spaced roof, of supporting means arranged across the tank near the top thereof, a water receptacle of a 100 105 110

contour similar to the contour of the tank having its walls snugly engaged with the inner surfaces of the walls of the tank and its bottom resting on the supporting means 5 so that the upper edges of the walls of the receptacle lie flush with the upper edges of the walls of the tank, and means for securing the walls of the receptacle and tank together.

In testimony whereof I affix my signature in the presence of two witnesses.

JOSEPH A. BUTCHER.
